UNITED STATES PATENT OFFICE.

WILLIAM A. WALKER, SR., OF ALLEGHENY, PENNSYLVANIA, ASSIGNOR OF SEVEN-SIXTEENTHS TO FRANK JOHNSTON, OF BEN AVON, PENNSYLVANIA.

FURNACE CONSTRUCTION.

No. 906,341.

Specification of Letters Patent.

Patented Dec. 8, 1908.

Application filed September 26, 1907. Serial No. 394,598.

To all whom it may concern:

Be it known that I, WILLIAM A. WALKER, Sr., a citizen of the United States, residing at Allegheny, in the county of Allegheny and State of Pennsylvania, have invented certain new and useful Improvements in Furnace Construction, of which the following is a specification, reference being had therein to the accompanying drawing.

10 My invention refers to improvements in furnace construction, more particularly the furnace of a locomotive boiler, and it has for its object to provide means for supplying superheated steam to the fire box to assist 15 combustion, fully consume the fuel or its by-products, preventing smoke, and reducing the cost of operation.

In the drawings: Figure 1 is a longitudinal vertical section partly in elevation of a locomotive boiler, indicated by the line I. I. of Fig. 2. Fig. 2 is a horizontal section indicated by the line II. II. of Fig. 1, the boiler tubes being partly broken away. Fig. 3 is a vertical cross section on the line III. III. of 25 Fig. 1. Fig. 4 is an elevation of the rear end of the boiler. Fig. 5 is an enlarged sectional detail view showing one of the jet pipes and its connections.

The invention is designed to employ superheated steam taken from the steam drum or any other point where dry steam may be insured, carried through a superheating coil located in the path of the hot gases, then conveyed backwardly along the boiler at each 35 side and introduced into distributing pipes having jet nipples leading into the firebox at opposite sides, with means for controlling the supply.

In the drawings 2 represents the shell of 40 the boiler provided with the usual flues 3 extending from the smoke box 4 to the firebox 5 and connected with the front and back sheets 6 and 7 in the usual way.

Dry steam is taken from the steam drum 45 cavity 8 by pipe 9 to a box or header 10 located above the back end of the boiler from which leads a pipe 11 having a controlling valve 12 the stem of which is provided with a hand wheel 13 within easy reach of the engineer or fireman. The box 10 is preferably 50 of broad flat construction, laid closely against the outer fire box shell for good heating effect, and within easy reach. Pipe 11 leads forwardly along the shell of the boiler,

thereby remaining hot, and is connected at 55 its forward end with a coil of pipe 14 located in the smoke box 4 and rigidly supported by any suitable frame or bracket 15 connected with the front of the main steam supply pipe 16 or in any other suitable manner. 60

The coil of pipes 14 may be of any number desired and are preferably located at an incline immediately in front of the ends of the flues 3 as shown, in which position the circulating contained steam will be highly superheated. The last coil of pipes 14 is connected with branch pipes 17 at each side extending through the shell 2 from which extend backwardly and downwardly pipes 18 connected at their rear ends with supply pipes 70 19. Said supply pipes 19 are located along each side of the firebox between the fire box shell 20 and outer shell 2 as shown, one of said pipes being about three inches above the other, and both being some distance 75 above the grate bars.

Each pipe 19 is provided with jet pipes 21 secured in and extending through the fire box shell 20 in any suitable manner as by tightening nuts and packing gaskets to make 80 a fluid-tight fit, and the jets are so located that the jets at one side are directed inwardly at points between or at one side of the jets of the other side. As above stated the rows of jets on opposite sides are on different levels, and by this arrangement the oppositely disposed inwardly directed jets deliver the superheated steam across the fire box without interference with each other, and at the same time transverse the entire 90 area of the fire box. By this arrangement the partly consumed gases or fuel of combustion and all cinders, smoke etc. pass upwardly to the flues through the zone of superheated steam. Intense heat of combustion 95 is thereby produced resulting in burning up all of the carbon of the fuel and completely consuming every part.

The invention is particularly adapted to furnaces fired with green fuel, as in locomotive practice. It prevents the escape of smoke, requires but a small part of the steam, and results in a great saving of coal.

The device may be adapted to other types of furnaces and may be changed or varied by 105 the skilled mechanic in different features or details, and I do not desire to be limited to the construction shown and described.

What I claim is:

1. In a locomotive boiler provided with a steam drum, the combination with the fire box having fuel supporting grates and outer and inner shells, of headers provided with jets extending inwardly through the inner fire box wall into the fire chamber above the grates, a superheating coil located in front of the boiler flues in the path of the gases of combustion of the furnace having distributing pipes connected at each side of the fire box with said headers, a steam box located above the outer shell of the fire box chamber, a pipe leading from the interior of the steam drum to said box, and a pipe leading from said box along the boiler shell to the superheating coil provided with a controlling valve and an operating device therefor, substantially as set forth. 35
2. In a locomotive boiler provided with a steam drum, the combination with the fire box having grates and outer and inner shells, of headers located between the said shells of the fire box provided with jets extending inwardly through the inner fire box walls into the fire chamber above the grates and arranged out of alignment with each other, a superheating coil located in front of the boiler flues in the path of the gases of combustion of the furnace having distributing pipes connected at each side of the fire box with said headers, a steam box located above the fire box chamber, a pipe leading from the interior of the steam drum to said box, and a pipe leading from said box along the boiler shell to the superheating coil provided with a controlling valve and an operating device therefor, substantially as set forth. 40
3. In a locomotive boiler provided with a steam drum, the combination with the fire box having fuel supporting grates, of headers provided with jets extending inwardly through the fire box walls into the fire chamber above the grates, a superheating coil consisting of a series of slopingly arranged horizontal tubes located in the path of the gases of combustion of the furnace in front of the boiler flues, the upper tube of said coil having oppositely disposed distributing pipes 45 connected with said headers at each side, and a conductor leading from the steam drum of the locomotive to said superheating coil, and embodying a steam box located above the fire box and a controlling valve and operating device therefor, substantially as set forth. 50

In testimony whereof I affix my signature in presence of two witnesses.

WILLIAM A. WALKER, SR.
